UNITED STATES PATENT OFFICE.

MORTIMER D. METCALFE, OF NEW YORK, N. Y., ASSIGNOR, BY MESNE ASSIGNMENTS,
TO GEORGE SEEBER, SR., OF ELIZABETH, NEW JERSEY.

SECONDARY CLOCK.

Application filed March 1, 1920. Serial No. 362,383.

To all whom it may concern:

Be it known that I, MORTIMER D. METCALFE, a citizen of the United States, and a resident of New York city, New York County, New York State, have invented certain new and useful Improvements in Secondary Clocks, of which the following is a specification.

The principal object of this invention is to provide a novel drive mechanism for intermittently operating mechanical devices, particularly electrical secondary clocks which are in circuit with master clocks and are driven by electrical mechanisms energized at regular intervals by the current flowing through a circuit which is made and broken by the master clock. Such clocks are well known and are adapted to be put to a great variety of uses, as in office buildings, schools, hotels, public buildings of all kinds, and in private dwellings.

An objectionable feature of clocks of this character heretofore designed or suggested is that a mechanical sound is made whenever the electrical driving mechanism is operated. This sound is sometimes caused by an armature oscillating between definite stops, sometimes by the clicking of pawls moving on ratchets, and sometimes in other ways. It is obvious that where quiet is desired, as for instance in hotel sleeping rooms, in schools, and in private dwellings, these sounds, however faint, are irritating to the occupants of the room.

The present invention provides a noiselessly operating electrical apparatus, particularly useful for driving clocks, having no parts moving between mechanical stops, and having no portion or part the operation of which may result in objectionable sounds.

A further object of the invention is to provide an apparatus of this class having a minimum number of parts, in which the parts are of simple character, which is readily accessible for cleaning and oiling, and which is of small size, rendering it convenient for wall clocks, desk clocks, mantel clocks, tower clocks, or clocks for any special purpose.

A further object of the invention is to provide a secondary electrical clock having two oppositely directed faces which are

adapted to be placed in a partition between two adjoining rooms and to have one face in each room, the hands of the clocks being mounted upon concentric shafts so that the clock faces are exactly opposite each other.

Another object of the invention is to provide a secondary clock which may be either a single or double faced clock, and which has in either instance a minimum number of parts enabling it to be made cheaply and easily, to be installed in small space, and enabling it to be cleaned and repaired conveniently.

The invention will be disclosed as applied to a wall clock having dials in each of the two adjoining rooms but it will be understood that the invention is not limited to this particular use but may be applied in many different ways. Also the present improved driving mechanism is described as applied to clock gearing with which it may be advantageously used, but it will be understood that the silent drive may be used in connection with other types of clocks and with other mechanisms. One form of the invention will be described herein and illustrated in the accompanying drawings in which:

Figure 1 is a central vertical section through a double faced clock showing the faces and the clock gearing;

Figure 2 is a section along the line 2-2 of Figure 1, part of the gearing being omitted for the sake of clearness;

Figure 3 is a longitudinal sectional view through the mercury tube, which comprises a portion of the drive mechanism;

Figure 4 is a reduced side view of the clock, the faces being omitted;

Figure 5 is a section on the line 5-5 of Figure 1;

Figure 6 is a view of part of the drive mechanism, as illustrated in Figure 5, the mercury tube being shown in a different position; and

Figure 7 is a top view of the clock.

The various shafts upon which the moving members are mounted are supported at their ends in similar parallel side plates 10, connected at their corners by rods 11. Extending horizontally through suitable openings in plates 10 and rotatably mounted therein,

are the main shaft 12 and the countershaft 13. On the main shaft are supported the main elements of the hand operating gearing and on the countershaft are mounted 5 the elements of the electrical drive mechanism for operating this gearing.

This electrical drive mechanism comprises essentially a Z-shaped armature 14 rigidly secured to the countershaft 13 and lying between the opposed pole pieces 15 of the two-coil electro-magnet 16. Also rigidly mounted on this shaft is a mercury tube 17, the axis of which makes an acute angle with the axis of the main or central portion of 10 the armature, as clearly illustrated in Figures 5 and 6. A quantity of mercury within the closed tube maintains it normally in the position shown in Figure 5 with its axis vertical, but when the magnets 16 are energized 15 the armature is moved to a position in which the longitudinal axis through its main portion assumes a horizontal position as shown in Figure 6, thereby rotating the shaft, causing the mercury tube 17 to assume an inclined position, as shown in Figure 6. The 20 curved wings 14' of armature 14 are for the purpose of insuring that the armature rotates in the proper direction when the magnets are energized, this direction being 25 clockwise as indicated by the arrows in Figures 5 and 6.

After the tube has been rotated into its inclined position the mercury will naturally run from the higher to the lower side, where 30 it will exert, due to the influence of gravity, a force tending to rotate the tube, armature and shaft into a vertical position exactly 35 180° from their starting point, and as soon as the magnets 16 are deenergized by the 40 circuit through the master clock being opened, the tube will rotate to this position.

In order to prevent oscillation of the tube after its rotation through 180°, which will 45 undesirably oscillate the hands of the clock, means is provided for retarding the flow of the mercury to the lower end of the tube after the magnet has been energized and the 50 tube brought to its inclined position. This retarding means prevents the weight of the mercury from exerting immediately a maximum torque about the countershaft, which 55 will be the case if the descent of the mercury from the high end to the low end is unimpeded, and might result in the tube oscillating when the magnets were deenergized. For this purpose valves 18 which open toward 60 the shaft 13 are provided in the mercury tube, each of these valves having a restricted opening 19. The obvious effect 65 of these valves is to permit the rapid flow of the mercury from the high end of the tube across the axis of the shaft 13, but prevents its immediate passage to the lower end of the tube. These valves are preferably made of fiber or rubber. By allowing the

mercury to pass only gradually into position where it will exert a maximum torque tending to rotate the shaft, it has less tendency to overrun the center of gravity when the magnets are deenergized, and to thereby cause oscillation of the shaft and the clock hands. The two-coil magnet 16 is supported from the four rods 11 by U-shaped members 20 preferably of sheet metal, the 70 positions of the U-shaped members on the rods 11 being determined by the spacing members 21 and 22.

It is desirable in the operation of secondary electric clocks that the hands be moved forward at least once each minute, 80 and in the operation of the present clock it is contemplated that the coils will be excited by the master clock at minute intervals, thereby causing a complete rotation of the shaft 13 once each two minutes. Gear- 85 connecting connecting the shaft 14 to the hands of the clock is therefore designed in this instance to move the hands forwardly the proper distance, that is, one minute space for the minute hand, each time the shaft 13 90 rotates through 180°.

In the drawings the minute hands are indicated at 23 and 24 respectively and the hour hands at 25 and 26 respectively. The minute hand 23 is mounted directly on the 95 shaft 12 and connecting the shafts 12 and 13 is a train of gears comprising gears 27, 28, 29 and 30, the gears 27 and 30 being mounted on and rotatable with shafts 13 and 12 respectively. Gears 28 and 29 are secured together and are mounted upon a short shaft 31 projecting from the plate 10. This gearing connects the shaft 13 to the shaft 12 with a 30 to 1 reduction, so that as the shaft 13 rotates 180° each minute the shaft 12 will 100 rotate 6° each minute, which is the proper angle of advancement for the minute hand 23. The hour hand 25 is mounted upon a sleeve 32 which sleeve is driven from the shaft 12 by reduction gearing of the usual 105 construction, the gears comprising this train indicated at 33, 34, 35 and 36 in the drawings.

Inasmuch as the hands 24 and 26 on the opposite clock faces must be rotated in a 115 direction opposite to the direction of rotation of the hands 23 and 25, reversing gearing must be utilized. The large gear wheel 30 which is rigidly mounted on the shaft 12 is provided on one side with a crown 120 gear 37 and, rigidly mounted upon the sleeve 38 which supports the minute hand 24 is a similar and oppositely facing crown gear 39. Interposed between the crown gears 37 and 39 is a frame or yoke 40 supported upon the shaft 12 and short shafts 41 and 42 extending from the plate 10. This frame 40 carries pinions 43, which mesh with the teeth of crown gears 37 and 39. Inasmuch as the pinions 43 are not 125 130

rotatable around the shaft 12, the motion of the crown gear 37 in one direction causes the crown gear 39 to move in the opposite direction and at an equal speed, which 5 speed is the speed of shaft 12, and it is therefore apparent that the minute hand 24 which is mounted upon the sleeve 38, which in turn supports the gear 39, will be moved at the exact speed of shaft 12 10 and the minute hand 23 but in the opposite direction.

Also rigidly mounted on the sleeve 38 is a gear 44 meshing with a large gear 45 mounted on the shaft 41. Secured to the 15 gear 45 and rotatable on the shaft 41 is a gear 46 which meshes in turn with gear 47 rigidly mounted upon a second or outer sleeve 48. This series of gears 44, 45, 46 and 47 comprises a reduction train where- 20 by the outer sleeve 48 is operated at one-twelfth the speed of the minute sleeve 38. Suitable spacing members may be utilized to maintain the various gears in proper position, but for the sake of clearness said 25 devices have been omitted from the drawings.

From the above description the operation of the clock will be apparent. The mercury tube is rotated by means of the 30 armature 14 through an angle of between 90° and 180° once each minute and as soon as the electrical circuit through the electromagnets is broken at the master clock, the mercury, which has in the meanwhile 35 changed position from the high to the low end of the tube, will, by force of gravity, complete the rotation of the tube and shaft 13 through 180°. Through the gearing described the minute hands are advanced 40 thereby one minute, and the hour hands one-twelfth of that amount.

The mechanism has no parts which are capable of producing mechanical sounds, however faint, in operation. No pawls are 45 necessary, no springs, and no means for positively limiting the movement of the rotating armature, inasmuch as the mercury tube is incapable of assuming any position other than a vertical one when the coils 50 are deenergized thereby advancing the hands of the clock the exact distance desired at each movement. It is obvious that changes may be made in the form and structure of the invention and I do not limit 55 myself to the exact form shown and described. For example, some other substance or body might be used as a shifting weight instead of the mercury utilized and other means might be utilized for retarding the 60 movement of the shifting weight.

Having thus described the invention what is claimed as new and desired to be secured by Letters Patent is:

1. Mechanism for intermittently rotating 65 a shaft or other rotatable element compris-

ing in combination, a rotatable member, means for rotating said member through an angle less than 180°, and second means supported by said member for continuing the rotation of said member to a position substantially 70 180° from the point at which said first means became active.

2. Mechanism for intermittently rotating a shaft or other rotatable element comprising in combination, a rotatable member, 75 means for rotating said member through an angle less than 180°, and second means comprising a shiftable weight supported by said member for continuing the rotation of said member to a position substantially 180° 80 from the point at which said first means became active.

3. Mechanism for intermittently rotating a shaft or other rotatable element comprising in combination, a pivoted rotatable member, 85 means for rotating said member through an angle less than 180°, and second means comprising a weight supported on said rotatable member and movable thereon from one side of its pivotal point to the other, for continuing the rotation of said member to a position substantially 180° from the point at which said first means became active.

4. Mechanism for intermittently rotating a shaft or other rotatable element comprising 95 in combination, a rotatable member, means for rotating said member through an angle less than 180°, and gravity actuated second means for continuing the rotation of said member to a position substantially 180° 100 from the point at which said first means became active.

5. Mechanism for intermittently rotating a shaft or other rotatable element comprising in combination, a rotatable member, 105 means for rotating said member, a pivotally mounted tube, means for rotating said tube through an angle less than 180°, and a weight within said tube adapted to move under the influence of gravity from one 110 side of said pivotal point to the other upon the initial movement of said member, for continuing the rotation of said member to a position substantially 180° from the point at which said first means became active. 115

6. Mechanism of the class described, comprising in combination, a rotatable shaft, a member fixed on said shaft, electrical means for rotating said shaft through an angle less than 180°, and second means for continuing the rotation of said member to a position substantially 180° from the point at which said first means became active. 120

7. Mechanism of the class described comprising in combination, a shaft, a member 125 mounted on said shaft, electrical means for rotating said shaft and member through an angle less than 180°, said means including an armature mounted on said shaft, and second means for continuing the rotation 130

- of said member to a position substantially 180° from the point at which said first means became active.
8. In an electrically operated secondary clock, gearing for actuating the hands of the clock, and means for intermittently operating said gearing, said means comprising rotatable member, electrically operable means for rotating said member through an angle less than 180°, and gravity actuated secondary means for continuing the rotation of said member to a position substantially 180° from the point at which said first means becomes active.
- 15 9. In an electrically operated secondary clock, gearing, means for intermittently operating said gearing, said means including a rotatable member, electrical means for rotating said member through an angle less than 180°, and gravity actuated secondary means for continuing the rotation of said member to a position substantially 180° from the point at which said electrical means becomes active.
- 25 10. Mechanism for intermittently rotating a shaft or other rotatable element including a pivotally mounted tube, means for rotating said tube through an angle less than 180°, a weight within said tube adapted to move under the influence of gravity from one side of said pivotal point to the other when said tube has been rotated, for continuing the rotation of said tube to a position substantially 180° from the point at which the rotating means became active, and means for retarding the movement of the weight toward the lower end of the tube after it has crossed the pivotal point, for the purpose set forth.
- 40 11. Mechanism for intermittently rotating a shaft or other rotatable element including a pivotally mounted member, means for rotating said member through an angle less than 180°, a weight supported on said member and adapted to move under the influence of gravity from one side of the pivotal point to the other when said member has been rotated, for continuing the rotation of said tube to a position substantially 180° from the point at which the rotating means became active, and means for retarding the movement of the weight toward the lower end of the member after it has crossed the pivotal point, for the purpose set forth.
- movement of the weight toward the lower end of the member after it has crossed the pivotal point, for the purpose set forth.
12. Mechanism for intermittently rotating a shaft or other rotatable element, including a pivotally mounted tube, means for rotating the tube through an angle less than 180°, mercury in the tube adapted to move under the influence of gravity from one side of the pivotal point to the other when the tube has been rotated, for continuing the rotation of said tube to a position substantially 180° from the position at which the rotating means became active, and means for retarding the movement of the mercury toward the lower end of the tube after it has crossed the pivotal point, for the purpose set forth.
13. Mechanism for intermittently rotating a shaft or other rotatable element, including a pivotally mounted tube, means for rotating the tube through an angle less than 180°, mercury in the tube adapted to move under the influence of gravity from one side of the pivotal point to the other when the tube has been rotated, for continuing the rotation of said tube to a position substantially 180° from the position at which the rotating means became active, and valve means for retarding the movement of the mercury toward the lower end of the tube after it has crossed the pivotal point, for the purpose set forth.
14. Mechanism for intermittently rotating a shaft or other rotatable element, including a pivotally mounted tube, means for rotating the tube through an angle less than 180°, mercury in the tube adapted to move under the influence of gravity from one side of the pivotal point to the other when the tube has been rotated, for continuing the rotation of said tube to a position substantially 180° from the position at which the rotating means became active, and means comprising an inwardly opening valve having a perforation therein, adjacent each end of the tube, for retarding the movement of the mercury toward the lower end of the tube after it has crossed the pivotal point, for the purpose set forth.

In testimony whereof I affix my signature.
MORTIMER D. METCALFE.
